UNITED STATES PATENT OFFICE.

ORLANDO KELSEY, OF BLACKWOOD, NEW JERSEY.

STEAM-GENERATOR.

SPECIFICATION forming part of Letters Patent No. 417,325, dated December 17, 1889.

Application filed April 16, 1889. Serial No. 307,463. (No model.)

To all whom it may concern:

Be it known that I, ORLANDO KELSEY, a citizen of the United States, residing at Blackwood, in Camden county, New Jersey, have 5 invented a new and useful Improvement in Steam-Generators, of which invention the following is a specification.

This invention relates to the sectional steam-generator for which Letters Patent No. 335,134 were granted to me February 2, 1886.

It consists, essentially, first, of a compartment steam-drum connected by pipes with the several individual sections composing the body of the generator, in combination with a 15 regenerator located in the crown of the furnace; second, in the combination, with the body of the generator, of an auxiliary generator herein termed a "steam-developer."

In the annexed drawings, Figure 1 is a front 20 elevation of the complete generator and inclosing masonry, front wall removed; Fig. 2, a side elevation of the generator, omitting the masonry; Fig. 3, a sectional elevation of the steam-developer; Fig. 4, a side and Fig. 5 an 25 end elevation of the steam-drum; Figs. 6 and 7, sections of the drum, the former on the line $x-x$ and the latter on the line $y-y$ of Fig. 5. Fig. 8 is a plan of the Y-pipes used for connecting the steam manifold pipes with the 30 steam-drum at both ends of the drum.

I have modified the form of the individual sections described in my said patent with the view of locating the regenerating-pipe in the crown of the furnace. I now give the sections 35 the form indicated in Fig. 1, wherein—

a represents the upright tubes, b the upper cross-tubes, and c the lower cross-tubes. To save piping, the tubes b are extended outside the masonry and connected with the steam- 40 manifolds d d' , which are in turn, by pipes e e' and Y-pipes e^2 e^3 , connected with the drum h at its opposite ends. The lower cross-tubes c of each section are curved to form a neck 45 and loop, as shown in Fig. 1, so that when the several sections are placed in position side by side there is formed a recess g' for supporting the regenerator g in the crown of the furnace. The relative proportions of the regenerator remain the same as described in my 50 said patent.

h represents the drum, to the shell of which

is given the form outlined in Fig. 5, with the view of increasing the area of its heating-surface. The interior of the drum is divided into three compartments h' h^2 h^3 , communicating by openings h^4 h^5 h^6 . 55

i and j represent manifolds through which water is supplied to the apparatus. They are placed directly below the legs of the sections, as shown in Figs. 1 and 2, and they act also 60 as mud-drums to the sections, any sediment collecting in them being readily blown out through pipe k .

l and l' represent steam-developers, each consisting of an exterior pipe m , Fig. 3, 65 through the capped or otherwise closed ends of which passes a pipe n . This pipe is connected with the water-supply, as shown, and is provided with the small slots or holes o , opening into the steam-space p , which is connected by open pipes q at each end of the developer with the steam-pipes e e' , leading to the drum h . The steam-developers l l' are extended through the sections above the cross-pipes c in order to give the greater compactness to the apparatus. They may, however, be located in the furnace below the cross-pipes c and supported by fire-brick brackets or hangers, their essential conditions being that they shall be below the water-line of the 70 generator, and that the steam-spaces shall be connected at each end to the drum h by open pipes or passages for the delivery of the steam generated in them. 75

r represents the steam-delivery pipe; s , a 80 pipe for conveying condensed steam from compartment h^2 of the drum into the water-leg of any of the sections. The steam generated in the several sections passes into the manifolds d d' , thence through pipes e e' e^2 e^3 into the 85 top compartment h' of the drum, thence down through the opening h^4 into compartment h^2 , where its more watery portions are deposited, the steam passing on down through the opening h^5 into compartment h^3 , thence by opening h^6 to and through the regenerator g , and thence to the delivery-pipe r . The developers l l' , being situated below the water-level maintained in the sections, are at the start full of water, which is by the action of the furnace 90 heat soon expelled, passing up through the pipes q into compartment h^2 of the drum, 95

whence it is led back through the pipe *s* into the water-manifold or into any of the sections of the generator. Sufficient water to supply the developers *l l'* enters the steam-space *p* through the small slots *o* of the inner or feed pipe *n*, and is rapidly converted into steam, which has a free-exit through the pipes *q* into the pipes *e e'*, and enters the drum along with the steam generated in the sections. In this way I am enabled to generate with rapidity and safety a large amount of steam with a comparatively small consumption of fuel.

A single developer or any desired number can be used.

15 I claim—

1. A steam-generator composed of several sections, each consisting of upright pipes *a* and cross-pipes *b c*, of which the lower pipe *c* is curved to form a recess *g'* in the crown of

the furnace, a drum *h*, divided into three communicating compartments, the steam-pipes connecting said sections with drum *h*, the re-generator *g*, located in the recess *g'*, and the condensation-pipe *s*, in combination, substantially as set forth.

2. In combination, a steam-generator consisting of several sections, a steam-drum *h*, divided into three communicating compartments, steam-pipes uniting said generator and drum, one or more steam-developers *l*, open pipes *q*, connecting the steam-space *p* of each developer with the drum *h*, and a pipe *s* for conveying water and condensed steam away from the drum, substantially as set forth.

20 25 ORLANDO KELSEY.
